DESIGN FOR A BELL

Stanley A. Bevin, East Hampton, Conn., assignor
to Bevin Bros. Manufacturing Co., East Ham-
pton, Conn., a corporation of Connecticut

Application October 8, 1937, Serial No. 72,077

Term of patent 14 years

To all whom it may concern:

Be it known that I, Stanley A. Bevin, a citizen
of the United States and a resident of East
Hampton, in the county of Middlesex and State
of Connecticut, have invented a new, original,
and ornamental Design for a Bell, of which the
following is a specification, reference being had
to the accompanying drawing, forming part
thereof, in which—

Figure 1 is a view in side elevation of a bell
showing my new design.

Figure 2 is an end view of the same.

The essential features of the design reside in
the double arrangement of bell bodies presenting
an ellipsoidal formation having a single annular
relatively narrow band at the equatorial line
thereof, said narrow band dividing said ellipsoid
into equal sections, each section being slightly
separated from the adjacent side of said narrow
band.

I claim:

The ornamental design for a bell, as shown and
described.

STANLEY A. BEVIN.
